UNITED STATES PATENT OFFICE.

RUDOLPH CONRADER, OF ERIE, PENNSYLVANIA.

GOVERNOR.

No. 821,157.

Specification of Letters Patent.

Patented May 22, 1906.

Application filed March 14, 1904. Serial No. 198,082

To all whom it may concern:

Be it known that I, RUDOLPH CONRADER, a citizen of the United States, residing at Erie, in the county of Erie and State of Pennsylvania, have invented new and useful Improvements in Governors, of which the following is a specification.

This invention relates to governors; and it consists in certain improvements in the construction thereof, as will be hereinafter fully described, and pointed out in the claims.

The invention is illustrated in the accompanying drawings as follows:

Figure 1 shows a central section of the governor; Fig. 2, a side elevation of the same; Fig. 3, a section on the line 3 3 in Fig. 2.

A marks the valve-chamber; a, the valve-diaphragm therein; B, the ordinary governor-valve; b, the valve-stem extending therefrom. Secured to the valve-chamber is the valve-frame A'. The valve-stem extends up into this frame and is secured to the yoke B'. The upper end of this yoke is provided with a step-bearing b', on which the pin C rests. The pin extends out through the governor-carrier M to a head-block c. The head-block c has the pins c', on which are pivoted links D. These links are pivoted, by means of the pins e, with the weights E, the weights forming the centrifugal element of the governor. The weights are driven with the carrier M by means of the gear m. This gear m is driven by the beveled gear n. The gear n is fixed on the shaft N. The drive-pulley O is arranged on the shaft N. The centripetal element of the governor is connected with it through the lever F, which engages the yoke B. The lever F is arranged on the rod f and has the extensions F' extending out without the governor-frame A'. Resting on the outer end of the extension F' is the spring G, which forms the centripetal element of the governor. The yoke H is arranged on this spring G and is extended by the pin h, which rests on the piston I in a pressure-cylinder I'. The springs H' are arranged at each side of the yoke H and normally hold the yoke in its normal position. The pressure-cylinder I' is connected with any fluid-pressure receiver connected with a pump controlled by the governor. It

enters the cylinder k through an opening K', passes, by the passage i', into the pressure cylinder or chamber I'. The passage i' is controlled by a needle-valve J. A vent i is provided for the chamber I'. By proportioning the passage i' and vent i the varia-

tion of the pressure in the receiver may be intensified. A piston K controls the valve J. It has the stem k' extending against the rock-lever L. The movement of the piston K is opposed by the spring l. This peculiar pressure device, in connection with the governor, does not form the special subject-matter of this application. Any pressure device may be used, if desired.

None of the structure so far as hereinbefore described forms any of the specific subject-matter for this application. The general features of the centrifugal governor are shown in my patent of November 14, 1899, No. 636,764, and some of the features of the pressure device are shown in my patent of December 25, 1900, No. 664,468.

In all governors, and particularly in the governor herein shown, difficulty has been experienced in oiling the carrier-bearing, the carrier M being journaled in the frame A'; and with the usual operation of the governor it is rotated rapidly. I have overcome this difficulty by providing the stem C with a passage c². The passage c² extends into a cavity m', formed between the carrier M and the pin c², this cavity forming a reservoir for a lubricant, as oil. A passage m² extends from this cavity to the carrier-bearing. An opening e' is arranged in the governor-weights immediately at the axis of the pin, so that oil may be introduced to the passage c² when the governor is stationary or in motion. The bearing between the pin and the carrier is also lubricated in this manner, as is also the step b'. I have also provided means for oiling the pivots of the links D. These links being adjacent to the cavity c² have the openings d, which are arranged to receive the overflow d, which are arranged to receive the overflow from the cavity c². Passages d' extend through the links to the joint formed on the pivot e. In this way the parts of the governor are completely lubricated, and the oil may be introduced while the governor is stationary or in motion.

In my patent of November 26, 1901, No. 687,450, I have shown and claimed automatic stop device for a pump-governor. In the present application I provide an improved form of automatic stop for pump-governor. The rod f of the lever F extends outwardly parallel with the shaft N. At its outer end there is arranged a finger Q, which is locked with the rod f by the pin q. The finger Q is in the path of a cam P. The cam P is journaled on the end a' of the part a², and the

journal of the cam is consequently practically concentric with the shaft N. An arm P' extends from the cam P and has the pulley P² arranged to ride on the belt (shown by the dotted lines) when the governor is operating normally. When the belt is disarranged, broken, or otherwise, the pulley P² forms a weight which drops, carrying with it the cam P. This operating upon the finger Q rocks the rod f and depresses the lever F, thus shutting off the governor. This operation is completed independently of the action of the speed or pressure governors. By making the rod f parallel with the shaft N the working pivots are brought into parallel, thus making a more convenient and efficient structure. It also brings the working parts of the governor so that they can be reached for attention and lubrication from one side—that is, the pressure device is in line with the belt and in position so that it can be reached from the belt side of the governor.

What I claim as new is—

1. In a governor, the combination with the centrifugal weights, the carrier for the same, a stem extending through the carrier, the top of the stem being exposed at the top of the governor, a centripetal element operating upon said stem, a governor-valve, a connection between the valve and the stem, said

stem being arranged at the axis of the governor and having a passage along its axis for conveying oil from the exposed top of the stem to the carrier.

2. In a governor, the combination of the 35 centrifugal weights, the carrier for the same, a stem extending through said carrier at the axis of the governor, links connecting said carrier with the weights, the top of the links being adjacent to the top of the stem, a centripetal element operating upon said stem, a 40 governor-valve, devices connecting the governor-valve with the stem, said stem being exposed at the top of the governor and being adjacent to the tops of the links, said stem 45 having a passage arranged at its axis to convey oil from its exposed top to the carrier of the governor, and said links having oil-channels extending through them, the channels in said links opening at points adjacent to 50 the opening in the stem whereby the overflow of oil in the stem enters the channels in the links.

In testimony whereof I have hereunto set my hand in the presence of two subscribing 55 witnesses.

RUDOLPH CONRADER.
